UNITED STATES PATENT OFFICE

97,829

DESIGN FOR LACE

George D. Boysen, Philadelphia, Pa.

Application October 23, 1935, Serial No. 59,180

Term of patent 3½ years

To all whom it may concern:

Be it known that I, George D. Boysen, a citizen of the United States of America, residing at Philadelphia, county of Philadelphia, and State of Pennsylvania, have invented a new, original, and ornamental Design for Lace, of which the following is a specification, reference being had to the accompanying drawing, forming part thereof, wherein,

The figure is a plan view of a piece of lace showing my new design.

I claim:

The ornamental design for lace, substantially as shown.

GEORGE D. BOYSEN.
